UNITED STATES PATENT OFFICE.

SAMUEL C. SIMS, OF STERLING, ILLINOIS.

MATERIAL FOR SURGICAL SPLINTS.

937,478.

Specification of Letters Patent. Patented Oct. 19, 1909.

Application filed October 22, 1903. Serial No. 178,137.

To all whom it may concern:

Be it known that I, SAMUEL C. SIMS, a citizen of the United States, residing at Sterling, in the county of Whiteside and State of Illinois, have invented new and useful Improvements in Material for Surgical Splints, of which the following is a specification.

This invention relates to surgical splints in which a cement material in a dry, unused state is incorporated in a fibrous and pliable material, and the primary object of the invention is the production of a quick-setting splint material of this character that can be conveniently handled in its commercial state and be ready for application to an injured part by moistening before applying, and which when set will form a tough porous body that will be more wholesome and agreeable to the injured part than the ordinary plaster splint.

A further object of the invention is to provide a splint material that will not require the complete encircling of the injured part thereby or its building up after the manner of a bandage in applying, and which when set will possess a yielding property and be capable of removal and replacement, thereby making provision for the swelling of the soft tissue in the neighborhood of the injured part and permitting access to the injured part at all times.

In the drawing, Figure 1, shows a view in perspective of a portion of the splint material, the same illustrating the process of building-up of the material and showing the layers of the plaster of paris for filling the adjacent layers of the fiber; and Fig. 2, shows a section taken on the line $\alpha-\alpha$ of Fig. 1.

In practicing the invention cotton batting is preferably employed on account of its light absorbent character, but it is obvious that other soft fibrous material compacted in like manner may be used. The cotton batting is separated or formed into thin sheets, the cotton being sufficiently compressed to cause it to hold together in sheet form. These sheets are indicated in the drawing by the numeral 1, and a strip of the required thickness is built up of them. As the building up process is progressing plaster of paris is spread on the top of each sheet

except the last, and in sufficient quantity to form a light layer 2 in addition to causing 55 some of the plaster to sift into the sheet upon which it is applied. The layer of the plaster is designed to further fill the sheet below it and also distribute itself partly into the sheet above it, so that ultimately the distribution of the plaster will be uniform 60 throughout the fiber and the union of the several sheets of cotton batting allowed to take place. To aid this distribution the sheets are subjected to vibration during the 65 process of construction but the jarring incident to the commercial handling of the material will be sufficient to effect this distribution and may be taken into consideration.

By the above-stated method of construction it is possible to incorporate within the cotton batting a quantity of plaster of paris which would not be possible by sifting the plaster into a strip of the batting of the thickness required for a splint owing to the 75 tendency of the plaster to sift through the material and leave but a small part adhering within the same, while such as would be deposited within said material would be so loosely held as to be readily dislodged to 80 such an extent in handling as to make it impracticable to use the material for the purposes intended. I am aware that it is not new to incase within a fabric plaster of paris to produce a splint, but it will be understood 85 that the present invention aims to thoroughly incorporate the plaster throughout the fibrous structure of cotton batting or an equivalent material, in a quantity not heretofore possible and in a manner to produce 90 the uniform distribution of the plaster, and furthermore to cause the uniform blending or uniting of the layers of the cotton batting of which the completed strip is formed, thus substantially effacing the layer 95 structure. The strip produced as herein set forth contains enough of the plaster as to permit its use without forming a bandage thereof, and is in convenient and ready form for handling and applying, it being only 100 necessary to soak the strip in water, squeeze out the excess water, and apply to the injured part, holding the same thereon with a bandage.

What I claim, is:—

As a new article of manufacture, a ma-

terial for surgical splints, comprising a plurality of thin layers of cotton batting, each layer having thoroughly incorporated therein dry powder of plaster of paris and 5 a layer of said powder between the respective layers of cotton batting, as and for the purpose set forth.

In testimony whereof I have signed my name to this specification in the presence of two subscribing witnesses.

SAM'L C. SIMS.
